Attorney
J. L. Walker

UNITED STATES PATENT OFFICE.

HOWARD M. SHERWOOD, OF VANDALIA, OHIO.

DRAG-LINE SCOOP-BUCKET.

1,395,988.

Specification of Letters Patent.

Patented Nov. 1, 1921.

Application filed January 27, 1920. Serial No. 354,508.

To all whom it may concern:

Be it known that I, HOWARD M. SHERWOOD, a citizen of the United States, residing at Vandalia, in the county of Montgomery and State of Ohio, have invented certain new and useful Improvements in Drag-Line Scoop-Buckets, of which the following is a specification.

My invention relates to excavating apparatus and more particularly to a scoop bucket for drag line excavators and means for controlling the bucket. The scoop bucket herein disclosed may be either an open type of bucket or one of closed type, that is open at one end only. It is particularly intended for operation in an outward direction by being dropped to its work near the foot of the boom, and drawn outward toward the end of the boom, in a direction reverse to that usually employed.

The object of the invention is to simplify the structure, as well as the means and mode of operation of drag line scoop buckets whereby they will not only be cheapened in construction, but will be more efficient in use, positive in operation, easily controlled, and unlikely to get out of repair.

A further object of the invention is to provide improved control means for the scoop bucket and to provide means whereby the bucket will automatically dump or discharge its load.

A further object of the invention is to provide improved harness for such a scoop bucket.

With the above primary and other incidental objects in view as will more fully appear in the specification, the invention consists in the features of construction, the parts and combinations thereof, and the mode of operation or their equivalents as hereinafter described and set forth in the claims.

Referring to the drawings, Figure 1 is a side elevation somewhat diagrammatic in character illustrating the mode of operation of the improved scoop bucket and the various features of control therefor. Fig. 2 is a perspective view of a closed type scoop bucket embodying the present invention. Fig. 3 is a detailed sectional view thereof. Fig. 4 is a detail view illustrating the control of an open type of bucket. Fig. 5 illustrates a

multiple purchase for the control line. Figs. 6 and 7 illustrate modifications.

Like parts are indicated by similar characters of reference throughout the several views.

While the scoop bucket forming the subject matter hereof has been shown in Fig. 1 as mounted upon an oscillatory supporting structure having an outwardly and upwardly projecting boom, as is commonly employed, it is to be understood that the scoop bucket may also be mounted upon an overhead cable or be connected between stationary supports or towers at the opposite ends of its path of travel. The supporting structure shown in Fig. 1 is for the purpose of illustration only, and to show the various positions assumed by the bucket at various stages of its operation.

In the drawings, 1 is the usual power plant mounted for rotary movement upon a base 2, and carrying an outwardly and upwardly extending boom 3. The power plant 1 embodies the usual power actuated winches or drums 4 and 5 for the drag line and bucket or control line respectively. The drag line extends from the winch or drum 4 upwardly to the guide sheave 6 at the end of the boom 3 and thence downward to the bucket, while the bucket line or control line is carried from the winch or drum 5 over a guide sheave 7, located adjacent to the foot of the boom and then to the bail of the bucket as hereinafter described. By the retraction and slackening of the drag and bucket line, the bucket is carried through its various operative movements.

The scoop bucket shown in Figs. 2 and 3, comprises a receptacle 8 opened only at one end as at 9. This bucket comprises four sides 10^a, 10^b, 10^c, and 10^d, and a bottom 11. When it is operated or digging the bucket reclines upon the side 10^b and is drawn open end forward until it is filled with excavated matter. In order to assist the excavation the forward edge of the bucket or scoop is provided with digging fingers 12. Fixedly attached to the forward end of the scoop or bucket is an arch 13. Pivotally connected adjacent to the bottom 11 and upper side 10^a of the bucket or scoop is an offset or L-shaped bail 14. The pivotal point 15 of the L-shaped bail 14 is both below and offset later-

ally from the center of gravity of the filled bucket when supported upright with its open end uppermost, as in position III of Fig. 1. Connected to the lower forward portion of the pivoted L-shaped bail 14 is the bridle 16 to which is connected the end of the drag line 17. It is understood that the bridle 16 comprises a chain or cable, the opposite ends of which are connected to the opposite forward corners of the bail, while the cable 17 is connected to the medial portion of the bight of such bridle. A bucket or control line 18 passing from the winch or drum 5 over the guide sheave 7 passes then over a second guide sheave 19, mounted in suitable bearings on the top of the pivoted bail 14 and extends therebeyond and is fixedly connected with the rigid arch 13 of the scoop bucket. The arrangement of the bucket line over the guide sheave 19 is such that as long as the bucket line 18 is held taut the scoop bucket arch 13 and bail 14 are held closely adjacent. If the bucket or control line is slackened only as the drag line 17 is retrieved, the control line being kept tight in the mean time, the bucket is drawn forward in a substantially horizontal position as shown at position I in Fig. 1. However, if while being drawn forth by the drag line, the control line 18 is slackened off, the engagement of the digging fingers 12 in the material to be excavated retards the lower forward edge of the bucket while the drag line draws the bail forward tending to tilt the scoop bucket downwardly and forwardly as shown in the position II, Fig. 1. By this manipulation of the control or bucket line the operator may cause the bucket to descend to greater or less degree into the material to be excavated thereby facilitating the excavation and the filling of the bucket. After the bucket has been sufficiently charged with excavating material the drag line 17 being retrieved, the bucket is drawn upwardly and forwardly, while the control or bucket line 18 is held comparatively tight, being relieved only as the drag line is retrieved thus the bucket is swung upward in a vertical position, thus retaining all the contents thereof. When the bucket has been carried to a point beneath the end of the boom as shown in position IV, and is suspended entirely upon the drag line, the control or bucket line is slackened off thus releasing the bucket or scoop in relation with the bail 14. The preponderance of the load of excavated material within the bucket being at the forward or outer side when the bucket is upright as shown in position III, Fig. 1, the bucket will automatically reverse itself through influence of gravity, as the control or bucket line is released, and will assume the position shown in position IV thereby discharging or dumping the load.

65 In order to return the bucket to its point

of operation, the bucket or control line is retrieved and the pull of the control line upon the rigid arch 13 of the scoop bucket, first reverses the position of the bucket about its pivotal connection 15, and when the bucket has assumed its normal position with the bail 14, the entire structure is drawn rearwardly and downwardly to the point of operation.

In a scoop bucket of the closed bucket type, air vents 20 are provided adjacent to the bottom thereof to permit the escape of air and also of water in the event that the operation is the dredging of the bottom of a lake or river. The arrangement herein disclosed gives constant control over the movement of the bucket enabling the operator to gage the depth of operation and it enables the movement of large bodies of excavated material.

In lieu of a closed type of bucket as shown in Figs. 2 and 3, an open bucket may be lifted and retained in horizontal position by proper manipulation of the control line as shown in Fig. 4. By receiving a series of strands of control line over suitable blocks or sheaves between the arch 13 and bail 14 as in Fig. 5, less tension will be required on the control line. It will be understood that considerable force or pull is exerted by the bucket in the digging operation. This is more effectively resisted by the use of a purchase or tackle as in Fig. 5, at the same time less power is required on the control line.

In Fig. 6 there is shown a modification in which, in lieu of the L-shaped bail 14, there are shown parallel forwardly extending arms 21 which may or may not be connected by a spreader 22 at their forward ends. The draft rigging 16^a is connected to the forward ends of the arms 21. In this construction, in lieu of a single control line 18, there is provided a bridle 18^a comprising two strands of cable separated by a spreader 23. These strands of cable each pass over the sheave 24 on the corresponding arm 21, and are attached to the bucket at 25. It will be obvious that by tightening or slackening the control cable 18, the bucket is turned about its trunnions 15 with the arms 21, causing it to assume a more or less inclined relation with the line of draft. In Fig. 7, the construction is quite the same except that the arms 21 are extended forwardly a considerable distance beyond the bucket, and joined at their forward ends to which the drag line 17 is attached. This extension of the arms 21 affords greater leverage and tends to decrease any wabbling or side motion of the bucket during the digging operation. The control cable is arranged as shown in Fig. 6 and heretofore described. In the constructions illustrated in Figs. 6 and 7, the bucket has been shown of the open type. It is to be understood that a closed type bucket may

be substituted in the constructions shown in Figs. 6 and 7, or an open bucket may be employed in the constructions shown in Figs. 1 to 5 inclusive.

- 5 From the above description it will be apparent that there is thus provided a device of the character described possessing the particular features of advantage before enumerated as desirable, but which obviously is 10 susceptible of modification in its form, proportions, detail construction and arrangement of parts without departing from the principle involved or sacrificing any of its advantages.
- 15 While in order to comply with the statute the invention has been described in language more or less specific as to structural features, it is to be understood that the invention is not limited to the specific details shown, but 20 that the means and construction herein disclosed comprise but one of several modes of putting the invention into effect, and the invention is therefore claimed in any of its forms or modifications within the legitimate 25 and valid scope of the appended claims.

Having thus described my invention, I claim:

1. In a drag line excavator, a scoop bucket, a forwardly extending drag line operatively 30 attached adjacent to the rear of said bucket, by which the bucket is actuated in its operative movement, and a retrieving line attached adjacent to the forward portion of the bucket and a guide upon the drag line 35 connection for said retrieving line, the oscillatory movement of the bucket about its connection with the drag line being controlled by the retrieving line.
2. In a drag line excavator, a bucket, a 40 drag line and a bucket control line, a draft connection for the drag line adjacent to the rear of the bucket, the bucket control line being connected to the bucket in advance of the drag line connection thereto, and means 45 for controlling said lines.
3. In a drag line excavator a bucket, a bucket control line and a drag line connected to the bucket in reversed spaced relation, and exerting their pulling influence 50 substantially in opposite directions thereupon, said lines each extending across the other to its draft connection with the bucket, and means for controlling said lines.
4. In a drag line excavator, a bucket, two 55 independent control lines connected to the bucket, in reversed spaced relation each line being adapted to tilt the bucket in opposite direction from the horizontal, the rear end of the bucket being tilted upwardly and 60 forwardly under the influence of one line, and the forward end of the bucket being tilted upwardly and rearwardly under the influence of the other line, and means for controlling said lines.
- 65 5. In a drag line excavator, a bucket, a
6. draft line connected to the bucket below and at one side of the center of gravity when the bucket is suspended in loaded condition, whereby the tendency of the bucket is to rotate about the line connection to inverted 70 position and a control line connected to the bucket above the center of gravity when so suspended and leading in a direction opposite to the direction in which the bucket tends to rotate, and means for controlling 75 said lines.
7. In a drag line excavator, a bucket, a bail pivotally attached thereto to the rear of and above the center of gravity when the bucket is in horizontal scooping position, a 80 forwardly extending drag line connected to the bail, a rearwardly extending bucket control line attached to the forward portion of the bucket and a guide on said bail engaging the bucket control line. 85
8. In a drag line excavator, a bucket, an L-shaped bail pivotally connected thereto to the rear of and above the center of gravity of the bucket when in its horizontal or digging position, a drag line connected to the 90 angle of said L-shaped bail and a bucket control line connected to the forward portion of the bucket and guided by the arch of the L-shaped bail. 95
9. In a drag line excavator, a bucket, a bail therefor extending over the top of the bucket and downwardly on each side thereof when the bucket is in horizontal charging position, and extending thence rearwardly and pivotally connected to the bucket near 100 the rear thereof, a forwardly extending drag line attached to said bail, and a rearwardly extending bucket line connected to the forward portion of the bucket controlling the oscillatory movement of the bucket and bail 105 in relation one with the other. 110
10. In a drag line excavator, a bucket, a drag line connected adjacent to the rear of the bucket, a bucket control line connected adjacent to the front of the bucket and adapted to regulate the oscillatory movement of the forward end of the bucket about the drag line connection to and from the line of draft of the drag line. 115
11. In a drag line excavator, a bucket, a drag line connected adjacent to the rear end of the bucket when in charging position 120 which becomes the bottom of the bucket when in conveying position whereby the bucket has a tendency to over topple through influence of gravity to discharge its contents, and a variable interconnection between the 130

forward end of the bucket when in charging position which becomes the top of the bucket in conveying position and the drag line by which the free end of the bucket is varied in 5 relation with the line of draft.

12. In a drag line excavator, a bucket, a drag line connected adjacent to the rear end of the bucket, the forward or receiving end of the bucket being free for oscillatory movement to and from the line of draft, and a bucket control line connecting the free forward end of the bucket and the drag connection by which the degree of divergence of the bucket and drag connection is varied. 10
13. In a device of the character described, an excavator bucket, means for tilting the rear end of said bucket upwardly and forwardly, during its operative action, including a drag line connected adjacent to the rear of the bucket, and leading forwardly therefrom, and means for limiting such tilting action of the bucket including a control 15
- 20

line attached to the front end of the bucket and adapted by its adjustment to vary the inclination of the bucket under the influence 25 of the drag line.

14. In a device of the character described, the combination with an excavator having a bail pivotally attached adjacent to its rearward end, a drag cable attached to said bail 30 and a control cable attached to the forward end of the excavator and guide means for said control cable movable with the excavator and drag cable for varying the relative angle of the excavator with the line of 35 draft.

In testimony whereof, I have hereunto set my hand this 19th day of November, A. D. 1919.

HOWARD W. SHERWOOD.
